OTTO GÜNTHER, OF ESSLINGEN, GERMANY.

VALVE.

Application filed May 29, 1924. Serial No. 716,545.

To all whom it may concern:

Be it known that I, OTTO GÜNTHER, a citizen of Germany, residing at Esslingen, Germany, have invented certain new and useful 5 Improvements in Valves, of which the following is a specification.

My invention relates to balanced valve bodies of shut-off valves and more especially of locomotive regulators.

10 It is an object of my invention to provide a valve body of the kind described in which the faces of the valve seat and valve body are in contact when the valve is closed or fully open and in intermediate positions of 15 the valve body are locked only with a pressure substantially equal to the steam pressure.

It is another object of my invention to 20 provide means for taking steam from several points of the steam space at the same time so as to avoid surging and priming.

In the drawings affixed to this specification and forming part thereof a device embodying my invention is illustrated diagrammatically by way of example.

In the drawings—

Fig. 1 is a vertical section of my novel valve on line A—B of Fig. 3.

Fig. 2 is a similar section on line C—D 30 of Fig. 3, both figures showing the valve closed.

Fig. 3 is a section on line E—F of Fig. 1, showing the valve open.

Fig. 4 is a plan view of the valve body.

35 Figs. 5 and 6 are developed projections of section G—H—J—K—G in Figs. 3 and 4 in the open and closed positions of the valve, respectively.

Fig. 7 is a part section of the valve body 40 and dome showing a pressure relief valve.

The casing 2 of the valve is secured to the shell of a boiler *a* by means of a flange formed at the top of the casing which is held between a seat formed on the boiler shell 45 and a dome 8 by means well known in the art and therefore not described in detail.

50 The valve body 1 is adapted to be rotated on a seat at the top of its casing 2 by means of the operating spindle 9 which projects at the bottom of the casing 2 and is provided with the usual lever 9' for turning the spindle. Stops 2' formed on the casing 2 limit the stroke of the lever 9.

55 An auxiliary valve 10 is secured to the upper end of the spindle 9 and adapted to rotate on a face formed in a recess at the

top of the valve body 1. Above this auxiliary valve a catch lever 15 is fixed on the spindle 9 and adapted to cooperate with lugs 15' on the valve 1. Holes 11 and 12 are 60 formed in the auxiliary valve 10 and the top wall of the valve body and adapted to register in certain relative positions of the valve body and auxiliary valve.

The valve body 1 and the casing are subdivided into a plurality of compartments by partitions extending from the faces of the casing and valve body. In the present case, the valve body and the casing are subdivided each into four quadrant chambers— 70 6, 6 and 13, 13 in the valve body and 5, 5 and 14, 14 in the casing—by partitions 20, 30, 40 and 50 in the valve body and 21, 31, 41 and 51 in the casing. In the valve body the said partitions extend from the valve face as far as the head of the valve body, while in the casing they extend from the valve seat to a horizontal web 2" formed in the casing. Ribs 22, 32, 42 and 52 in the valve body and 23, 33, 43, and 53 in the 80 casing which do not extend as far as the partitions 20, 21 etc., are equally spaced between said partitions and provided with ground faces like the partitions. The chambers 5, 5 in the casing are connected with the steam space of the boiler *a* and the chambers 14, 14 in the casing are connected with the inlet pipe 4. Holes 7 in the walls of the chambers 6, 6 of the valve body 1 connect the said chambers with the dome 8 when the 90 valve is closed. In this position, as shown in Fig. 5, the chambers 5, 5 in the casing register with the chambers 6, 6 in the valve body so that steam flows from the chambers 5, 5 to the chambers 6, 6 and into the dome 95 8 through the holes 7.

To open the valve the spindle 9 is rotated until the holes 11 in the auxiliary valve 10 register with the holes 12 in the valve body. The valve body remains stationary. The 100 holes 12 in the valve body are connected with each of the chambers 6, 6 and 13, 13 so that steam flows from the chambers 5, 5 and 6, 6 into the dome 8 and from the dome to the chambers 13, 13 and the pipe 4. 105 This balances the pressures on the outside and inside of the valve body 1, the pressure difference on its inside and outside being reduced approximately in proportion to the ratio of the areas of the holes 7 and the 110 holes 11, 12.

On further rotation of the spindle 9 the

valve body is engaged and rotated by the catch lever 15 connecting the chambers 5, 5 and 14, 14 in the casing 2 with the chambers 6, 6 and 13, 13 in the valve body until in the full open position shown in Fig. 6 the partitions in the valve body and casing coincide with the ribs in both.

It will appear from this description that in the full open as well as in the closed position of the valve the faces of the valve body and valve seat are inaccessible to impurities in the boiler water carried by the steam so that they are not subject to wear and will remain in good condition for a long time, particularly in cases where the valve is not operated frequently as in superheated steam locomotives having a separate regulator for superheated steam where the valve is nothing but a shut-off valve for the saturated steam, being opened and closed only when the locomotive is put on and off duty.

In case of back pressure in the inlet pipe as may occur in locomotives, the valve body is able to rise from its seat to relieve the pressure due to a slight clearance between the upper side of the lever 9 and the under side of the casing 2.

In locomotives where the engine is reversed to act as a brake when negotiating long gradients, the pressure in the inlet pipe may exceed the pressure in the boiler. For locomotives of this type the holes 7 are omitted and the relief valve 16 shown in Fig. 7 is provided. This is a double seated valve connecting either one of the chambers 13 or one of the chambers 6 with the space between the valve 1 and the dome 8. This allows the excess pressure in that chamber 13, during braking or from other cause, to escape into the dome 8 so that the valve body is forced on its seat in the casing 2. The pressure in the inlet pipe 4 is limited to maximum boiler pressure by a safety valve (not shown). In normal operation steam pressure may pass from the boiler through space 6 and by the valve 16 to the space between the valve 1 and dome 8.

As steam is taken from the steam space of the boiler at several points due to the arrangement of the chambers 5 surging which might occur when the valve is suddenly opened and priming are prevented.

I wish it to be understood that I do not desire to be limited to the exact details of construction shown and described, for obvious modifications will occur to a person skilled in the art.

I claim:—

1. Shut-off valve comprising a valve seat, a valve body, means for displacing said valve body on said seat, faces on said valve body and said seat adapted to effect steam tight closure and so arranged as to coincide when said valve body is in fully open and closed position, respectively, and means for

balancing the pressures acting on said valve.

2. Shut-off valve comprising a valve seat, a valve body, means for displacing said valve body on said seat, a dome secured on said seat and encasing said valve body, means for connecting the inside of said valve body with said dome, faces on said valve body and said seat adapted to effect steam tight closure and so arranged as to coincide when said valve body is in fully open and closed position, respectively. 70

3. Shut-off valve comprising a valve seat, a valve body, means for displacing said valve body on said seat, a dome secured on said seat and encasing said valve body, 80 chambers formed in said valve body and said casing, means for connecting one of the chambers in said valve body with said dome, faces on said valve body and said seat adapted to effect steam tight closure and so arranged as to coincide when said valve body is in fully open and closed position, respectively. 85

4. Shut-off valve comprising a valve seat, a valve body, means for displacing said valve body on said seat, a dome secured on said seat and encasing said valve body, chambers formed in said valve body and said casing, means for connecting one of the chambers in said valve body with said dome, 95 an auxiliary valve for supplying fluid under pressure to one of the chambers in said valve body, faces on said valve body and said seat adapted to effect steam-tight closure and so arranged as to coincide when 100 said valve body is in fully open and closed position, respectively.

5. Shut-off valve comprising a valve seat, a valve body, means for displacing said valve body on said seat, a dome secured on 105 said seat and encasing said valve body, chambers formed in said valve body and said casing, a pressure relief valve connected with one of said chambers, means for connecting one of the chambers in said valve body with said dome, faces on said valve body and said seat adapted to effect steam-tight closure and so arranged as to coincide when 110 said valve body is in fully open and closed position, respectively. 115

6. A rotary valve comprising a valve body and valve seat, partitions in said body and seat forming chambers, the ends of said partitions being adapted to make steam-tight connection between said body and seat, a dome encasing said valve body, one of said chambers having a port connecting said dome with the respective chamber, a rotary auxiliary valve adapted to cooperate with said valve body, said auxiliary valve and said valve body being provided with ports adapted to connect one of the chambers in said valve body with said dome, means for rotating said auxiliary valve and means for transmitting its rotation to said valve body. 120 125 130

7. A shut off valve comprising a valve seat having an annular row of alternately disposed inlet and outlet ports each having a valve seat portion dividing the port into two parts, a rotary valve body having a series of U-shaped passages terminating in ports in the surface thereof adapted to engage with said valve seat, whereby said valve when in open position connects one part of each inlet port with one part of an adjacent outlet port, and when in closed position connects one part of each inlet and exhaust port with the other part of the same port.
8. A shut off valve comprising a valve seat having an annular row of alternately disposed inlet and outlet ports each having a valve seat portion dividing the port into two parts, a rotary valve body having a series of U-shaped passages terminating in ports in the surface thereof adapted to engage with said valve seat, whereby said valve when in open position connects one part of each inlet port with one part of an adjacent outlet port, and when in closed position connects one part of each inlet and exhaust port with the other part of the same port.
9. A shut off valve comprising a valve seat having an annular row of alternately disposed inlet and outlet ports each having a valve seat portion dividing the port into two parts, a rotary valve body having a series of U-shaped passages terminating in ports in the surface thereof adapted to engage with said valve seat, whereby said valve when in open position connects one part of each inlet port with one part of an adjacent outlet port, and when in closed position connects one part of each inlet and exhaust port with the other part of the same port, a dome covering said valve, said valve having an opening therethrough from one of said U-shaped passages to the interior of the dome.
10. A shut off valve comprising a valve seat having an annular row of alternately disposed inlet and outlet ports each having a valve seat portion dividing the port into two parts, a rotary valve body having a series of U-shaped passages terminating in ports in the surface thereof adapted to engage with said valve seat, whereby said valve when in open position connects one part of each inlet port with one part of an adjacent outlet port, and when in closed position connects one part of each inlet and exhaust port with the other part of the same port, a dome covering said valve, said valve having an opening therethrough from one of said U-shaped passages to the interior of the dome, and a valve-controlled opening between another of said U-shaped passages and the interior of the dome.

In testimony whereof I affix my signature.

OTTO GÜNTHER.
